(57) **CLAIM**

The ornamental design for an eye shield frame, as shown and described.

DESCRIPTION

FIG. 1 is a perspective view of an eye shield frame of my new design; and,

FIG. 2 is a top view thereof.

The broken lines in the drawings are included for the purpose of illustrating unclaimed features and form no part of the claimed design.

1 Claim, 2 Drawing Sheets

FIG. 1

FIG. 2
